UNITED STATES PATENT OFFICE.

JOHN SELLERS BANCROFT AND MAURITZ C. INDAHL, OF PHILADELPHIA, PENNSYLVANIA, ASSIGNEES TO LANSTON MONOTYPE MACHINE COMPANY, OF PHILADELPHIA, PENNSYLVANIA, A CORPORATION OF VIRGINIA.

TYPE-MATRIX-SIDE-GROOVING MACHINE.

980,903.

Specification of Letters Patent. Patented Jan. 10, 1911.

Application filed April 16, 1909. Serial No. 490,229.

To all whom it may concern:

Be it known that we, JOHN SELLERS BANCROFT and MAURITZ C. INDAHL, of Philadelphia, in the county of Philadelphia and State of Pennsylvania, have invented a certain new and useful Improvement in Type-Matrix-Side-Grooving Machines; and we do hereby declare the following to be a full, clear, and exact description of the same, reference being had to the accompanying drawings, forming a part of this specification, and to the figures and letters of reference marked thereon.

The invention relates generically to automatic milling or shaping machines and is embodied in a machine specially designed to automatically, expeditiously and accurately produce the suspension and alining grooves or slots in the sides of type matrices such as are employed in what is known as the cellular die case (Patent No. 784,245 dated March 7, 1905).

The grooves on diametrically opposite sides of the matrix are symmetrical and in parallel planes, intersecting the other pair of grooves at right angles, the two sets or pairs differing in width and, if required, in depth also, and in the process of manufacture the side grooving is usually performed after the matrix and conical centering cavities have been formed in opposite ends of the block.

A very high degree of accuracy is demanded both in locating and dimensioning the grooves to the end that the matrices shall be interchangeable and the characters retained in justified position in the die case; and it is also required that distortion and mutilation of the matrix block should be guarded against, all of which objects are automatically and expeditiously attained by the improvements hereinafter fully described and the novel features pointed out in the appended claims.

In the accompanying drawings illustrating a preferred form of embodiment of said invention: Figure 1 is a perspective view of the complete machine, the lower ends of the supporting legs being broken away and omitted. Fig. 2 is a top plan view Fig. 3 a front elevation and Fig. 4 a right end elevation of the machine. Fig. 5 is a vertical section through the blank posi-

tioning and holding devices and the centering devices. Fig. 6 is a top plan view partly in section of those parts of the machine operating immediately upon the matrices including the feeding and delivering devices, the translating devices, the centering, gaging and rotary clamping mechanism and milling cutters. Fig. 7 is a longitudinal section through the matrix centering and placing devices. Fig. 8 is a detail view showing a section of the matrix centering spindle and its bearing. Fig. 9 is a longitudinal section of the rotary matrix holder or chuck and gage. Fig. 10 is a similar view with the chuck open and gage advanced to discharge the matrix. Fig. 11 is a perspective view of the chuck rotating and locking devices. Fig. 12 is a front elevation of the gaging locking means. Fig. 13 is a section through the chuck spindle in a plane intermediate the pawl and its carrying pinion and looking to the right or toward the pawl controller. Fig. 14 is a similar view taken to the right of the pawl and looking toward the pinion. Fig. 15 is a detail section through a portion of the pinion pawl and the pawl controller. Fig. 16 is a face or end view of the rotary matrix chuck or clamp. Fig. 17 is a transverse section through the chuck spindle in the plane of the pivot of its movable jaw. Fig. 18 is a similar view in the plane of the actuating pin. Fig. 19 is a vertical section in a plane to one side of and parallel with the translating jaws. Fig. 20 is a detail view of a portion of the actuating devices for the translating jaws. Fig. 21 is a transverse vertical section through the translating mechanism. Fig. 22 is a perspective view of the translating devices with the side plate removed and the vertically reciprocating guide in section. Fig. 23 is a perspective view of the clamping jaws of the translating devices with blank and finished matrices in position. Fig. 24 is a longitudinal section through the bearing for the spindle of one of the milling cutters. Fig. 25 is a transverse section of the milling cutter spindle and its bearing showing the means for effecting the lateral adjustment. Figs. 26 to 31 inclusive are diagrammatic views illustrating the translating jaws, matrix and milling cutters in different positions. Fig.

32 is a perspective view of the finished matrix. Fig. 33 is a perspective view of the transfer devices at the exit of the supply and entrance to the receiving galley, the 5 translating jaws and cover plates being omitted. Fig. 34 is a vertical section through the transfer devices of Fig. 33 in the plane of the transverse pusher together with the translating jaws in position to receive and discharge the matrices. Fig. 35 10 is a section on the line $x-x$, Fig. 34. Fig. 36 is a perspective view of the block forming the discharge gate of the supply galley. Fig. 37 is a sectional view corresponding 15 with Fig. 35 but with the pusher advanced to deposit the finished matrix in the receiving galley. Fig. 38 is a perspective view of the entrance to the receiving galley. Fig. 39 is a detail perspective of the transverse 20 pusher. Fig. 40 is a similar view of the pusher at the entrance to the receiving galley. Fig. 41 is a side view of the cams and connections for the translating jaws. Fig. 42 is a side view of the cam and 25 connections for the transverse pusher. Fig. 43 is a side view of the cam and connections for the guide of the translating jaws. Fig. 44 is a side view of the cam and connections for the centering spindle. Fig. 45 is a side view of 30 the cam and connections for the locking bolt of the matrix chuck. Fig. 46 is a side view of the cam and connections for the chuck actuating devices. Fig. 47 is a side view of 35 the cam and connections for the chuck rotating devices. Fig. 48 is a side view of the cam and connections for reciprocating the milling cutters.

Like letters of reference in the several figures indicate the same parts.

40 For purposes of description the machine illustrated may conveniently be divided into its integrant parts as follows: the milling or grooving devices; the blank or matrix positioning and holding devices; the translating 45 mechanism; the matrix supplying and receiving galleys; the means for transferring the matrices, one at a time, from the supply galley to the translating devices and from the latter to the receiving galley; and 50 the actuating devices for producing and controlling the action of the several mechanisms.

The matrix block prior to the side grooving is in the form of a parallelepiped in one 55 end of which the matrix cavity has been formed and in the opposite end a central conical depression or seat for the reception of the centering pin of the type machine, and the machine about to be described is 60 specially designed to form the grooves 1, 2, Fig. 32, whereof the narrower parallel grooves 1 on opposite sides run into and intersect the wider parallel grooves 2 on the remaining two sides.

65 The milling or grooving mechanism in-

cludes two rotary cutters 3, 4, of which the first corresponds in width with grooves 1 and the second with grooves 2. Each cutter is removably secured to one of two arbors 5, the latter supported in parallel relation in 70 bearings on a carriage 6 movable vertically in guides upon the frame. Each of said arbors 5 is eccentrically supported in a revolute sleeve or bearing 7, the latter carrying a worm wheel 8 engaged by a worm 9 supported in bearings on carriage 6, whereby said sleeve may be turned to adjust the arbor and cutter laterally for varying the depth of the cut. The arbor 5 is held against longitudinal displacement within 75 sleeve 7 by being confined between a collar and nut at opposite ends of said sleeve, and the latter is provided with adjusting devices, such as nuts 10, for varying its longitudinal 80 position.

To the rear end of each arbor 5 is attached one end of a flexible and extensible coupling 11 the opposite end whereof is connected to one of a pair of shafts supported in bearings on the frame and each provided with a pulley 12 or equivalent driving mechanism. In the preferred form illustrated the pulleys 12 are driven in relatively opposite directions by the driving belt 13, the latter passing first beneath the lower pulley, thence up and 90 around the upper pulley and down and around pulley 14. By this arrangement both cutters are caused to reciprocate in the same path from opposite ends thereof so as to alternately engage the matrix, the latter 95 being accurately positioned by the holding devices, and, in the interval between successive applications of the cutters, turned about its axis through 90° to successively present adjacent sides in the path traversed by one 100 or the other of said cutters, as will presently appear.

The matrix positioning and holding devices include a clamp or chuck and an opposed centering device between which the 110 matrix is supported in proper relation to the path of the cutter during the formation of successive grooves in its sides, and means for intermittently rotating said clamp or chuck, to present successive faces or sides of the 115 matrix to the action of the cutters as will now be explained.

Supported in a bearing or bearings on the frame and provided with suitable means for preventing longitudinal movement therein, 120 is a hollow spindle or sleeve 16, the axis whereof is preferably in parallel with and to one side of those of the cutter carrying arbors 5. The end of sleeve 16 adjacent the cutters is equipped with a removable head or plate 17 carrying two radial and independently adjustable jaws 18, the inner or adjacent ends whereof are disposed at a right angle. Opposing jaws 18 is a movable jaw 19 provided with an angular seat 20 and 130

carried by a lever 21 pivotally supported and operating within sleeve 16, said lever being furnished with an inclined groove or way 22 in which rides a pin 23 carried by a rod 24 within said sleeve. This rod 24 extends beyond sleeve 16 and is engaged by a spring 25, the latter operating to retract said rod in a direction to advance jaw 19 toward the angular seat formed by jaws 18. 5 Head 17 is also provided with a guide 26 for the reception of a longitudinally movable block 27 the latter attached to a slide 28 within sleeve 16 in position to be engaged by rod 24 when the latter is advanced to retract jaw 19 and thus open the chuck. Block 27 serves as a gage for determining the longitudinal position of the matrix relative to the jaws of the chuck when inserted in the latter, and as an ejector for the matrix when 10 the jaws of the chuck are opened, to which ends the slide 28 to which said block is attached is free to move within sleeve 16 between rod 24 and guide 26, the rearward movement being limited by the contact of block 27 with its guide so that when the matrix is inserted between the jaws of the chuck, block 27 will be moved back until arrested by its guide, thereby determining the 15 position of the matrix, and when rod 24 is advanced to open the chuck, it will engage slide 28 and advance block 27 to eject the matrix from between the jaws of the chuck. 20

Opposite the chuck and in axial alignment therewith are the centering and matrix seating devices. These include a spindle 30 supported in suitable bearings on the frame and provided with a conical point adapted to enter the cone hole in the base of the matrix. Surrounding the pointed end of spindle 30 25 is a pusher in the form of a disk or plate 31 carried upon rods 32 lying in grooves in the periphery of said spindle, the rear ends of said rods being attached to a collar 33 mounted upon the reduced rear end or portion of spindle 30.

The end of spindle 30 extends through a casing 34 attached to the frame, and the collar 33 is located within said casing, the latter limiting the forward movement of the 30 spindle. To spindle 30 in rear of collar 33 is adjustably secured a collar 35 working in casing 34 and between said collars (33, 35) is interposed a spring 36. An actuating lever 37 engages an adjustable collar 38 fast upon spindle 30, and a guard 39 fast on the frame surrounds the conical point of spindle 30 when the latter is retracted to permit the entrance of a matrix between the chuck and centering spindle, the function of said guard 35 being to prevent engagement of the matrix with the point of the spindle and consequent mutilation of either matrix or spindle. When spindle 30 is retracted for the admission of a matrix to the chuck, collar 33 is 40 engaged by the shoulder at the junction of

the main and reduced sections of said spindle to withdraw plate 31 and the point of the spindle within guard 39, as represented in Fig. 7. The matrix having been presented in position between spindle 30 and the chuck, 70 lever 37 is actuated to advance said spindle, the point of the latter entering the cone hole in the matrix, and plate 31 at the same time engaging the end of the matrix to force the latter into the chuck. During this movement the matrix is supported by its ends between the parallel faces of plate 31 and gage block 27, the latter held to place by the friction of slide 28 and yielding to the pressure of the matrix until arrested by its guide, 80 whereupon, by the continued movement of spindle 30, the conical point of the latter is seated in the cone hole. The matrix being thus properly positioned, the movable jaw of the chuck is advanced to close the chuck 85 and clamp the matrix, the spindle being maintained in its forward or centering position while the cuts are being formed. Thus the preliminary seating or centering of the matrix is performed by the spring actuated 90 plate 31 and gage 27 acting upon the relatively broad ends of the matrix before the conical spindle is seated to effect the final centering of the matrix and to afford support to the end of the latter remote from the 95 clamping jaws of the chuck.

The mechanism whereby the chuck is intermittently rotated and accurately positioned, to present successive sides of the matrix to the cutters, is applied to sleeve 16 and in the preferred form of embodiment illustrated includes a disk 40 provided with four equally spaced peripheral notches 41, a locking bolt 42, a pinion 43 carrying an engaging pawl 44, a disk 45 provided with 100 equally spaced peripheral notches 46, and means for actuating the pinion and controlling the engagement of its pawl with disk 45. Disks 40 and 45 are fast on sleeve 16 while pinion 43 is free to oscillate thereon 105 and when advanced with its pawl 44 seated in one of the notches in disk 45 it carries the sleeve with it. Locking bolt 42, Fig. 12, is movable longitudinally between parallel bearings or ways on the frame its engaging end or point being provided with opposite converging faces adapted to enter corresponding notches in disk 40.

To prevent accidental displacement of the chuck when locked in any of its four positions of adjustment bolt 42 is constructed in two sections, the outer section having its rear portion reduced or cut away on one side to form an incline 47 and shoulder 48. The rear section of said bolt is provided with a 115 tongue 49 one face whereof is inclined, as at 50, to correspond with the incline 47 and provided with an overlapping or hook portion 51 beyond shoulder 48. The bearing on the frame facing incline 50 serves as the 120

gage or datum line for determining the position of the chuck when said bolt engages and is seated in notch 41, the arrangement and angle of inclines 47 and 50 being such that when the rear section of the bolt is moved in a direction to withdraw the engaging section from the notch 41 its hook portion 51 will engage shoulder 48 after the inclines separate slightly to loosen the bolt 10 in its bearings; and when the motion of the rear section is reversed to project the bolt, the inclines will be reengaged to advance the front section, the two moving easily in their bearings until the engaging end is seated in notch 41 when by a continued pressure upon the rear section the front or engaging section will be firmly clamped against one side bearing, to wit, that one facing incline 50 and constituting the gage 15 for the final positioning of the chuck.

The means controlling the movement and engagement of pawl 44 include the following devices: The pawl arm 53 carries a pin 54 and is provided with a toothed segment 20 concentric with its pivot 56 and gearing with a similar segment 57 on an arm 58, the latter also pivoted to pinion 43 and provided with a pin 59, the arrangement being such that arms 53 and 58 will move in 25 unison in the same direction so that pins 54 and 59 will stand equidistant from the axis of pinion 43 in all positions of adjustment. Guided to reciprocate in bearings on the frame is a slide or yoke 60 provided with 30 a curved way 61 to receive pins 54, 59, one or the other whereof is at all times within said way. Pinion 43 is engaged by a rack 35 62 movable in guides on the frame and operating at predetermined intervals to 40 oscillate said pinion back and forth. When the pinion reaches one extreme of its movement, say the end of its feeding stroke, locking bolt 42 advances and is seated in notch 41, and way 61 is elevated and through its 45 engagement with pin 59 causes the retraction or withdrawal of pawl 44 (as indicated by the dotted lines in Fig. 13, and full lines in Fig. 14) whereupon the pinion is rotated to the opposite extreme, to retract pawl 44 50 and bring the latter opposite the next notch in disk 40. During this movement pin 59 of arm 58 passes from way 61, after pin 54 of arm 53 has entered therein, and said pin 54 is brought to such a position that upon 55 the movement of way 61 toward the axis of pinion 43 pawl 44 will be seated in the notch 41 registering therewith where it will be positively held during the next succeeding advance of pinion 43 by the engagement 60 of said way with pins 54 and 59, thus providing an intermitting feed in which the engaging pawl is positively moved and held in engagement with the driven member during its forward or operating excursion and 65 then positively withdrawn and held in re-

tracted position, free of the driven member, during the return of the pawl to initial position.

During the partial rotation of the chuck, effected by the mechanism described, the jaws remain closed but the pressure upon spindle 30 is slightly relaxed so as to permit free rotation of the matrix while still supporting the latter axially against displacement. 75

The completed matrix when delivered from the chuck is received by the translating devices, the latter having previously been charged with an ungrooved matrix which it presents in position to be entered 80 into the chuck through the action of plate 31 or spindle 30, after which the completed matrix is carried to a position where the transferring means operate to deliver an ungrooved matrix from the supply galley to 85 said translating devices, and to deliver the completed matrix to the receiving galley, as will now be explained.

The translating devices include a frame 63, pivotally attached at its rear end, as at 64, 90 to a carriage 65, the latter reciprocating in bearings on the frame and provided with a housing 66 in which frame 63 is guided in its movement upon pivot 64, the arrangement being such that frame 63 is permitted 95 a two way movement in a single plane. An adjusting screw 67 limits the movement of frame 63 in one direction, and the movement of carriage 65 is limited in one direction by engagement with a gaging abutment 68 and 100 in the other by an adjusting screw 69, the one for positioning the matrix holding devices relative to the chuck and centering spindle and the other with relation to the matrix transfer devices or pusher. 105

Frame 63 carries a fixed block 70 located intermediate two oppositely movable levers 71, 72, each of the latter provided with a lip 73 and coöperating with a projection 74* on block 70 to form two pairs or sets of clamping jaws. To the rear end of each lever 71, 72, is pivotally attached one end of an actuating rod or link 74, the latter provided with guiding sections 75 arranged between bearings 76 on frame 63, and to each of said bars is coupled a spring 77 tending to move its bar in a direction to advance the jaw end of its lever toward the complementary member of the clamp. The closing movement of the jaws under the action of their 115 springs is limited by block 70 with the opposite ends whereof said jaws contact in the absence of a matrix. 120

The front end of frame 63 *i. e.*, that nearest the chuck is fitted to a bearing in a transversely movable slide 78 by means of which the jaw carrying frame 63 is caused to vibrate upon its pivot to bring said jaws alternately into register with the chuck, and upon the carriage 65 is mounted a lever 79 125 130

in position to engage either jaw actuating rod 74 when brought into register therewith by the displacement of frame 63. Frame 63 is movable transversely of the axis of sleeve 16, its jaws traversing a path intermediate the chuck and centering spindle. When in normal position, as represented in Fig. 19, the clamping jaws are withdrawn from the chuck and elevated to bring the actuating rod 74 of the lower clamp in register with lever 79 to permit of the opening of said clamp for the reception of a blank matrix; and when carriage 65 is moved to advance the clamps into the space between the chuck and centering spindle, and slide 78 is actuated to bring either clamp into register with said chuck, the actuating rod 74 pertaining to the clamp at the time opposite the chuck will be in register with lever 79 and in position to be operated thereby to open the clamp for the reception or delivery of a matrix.

To protect the clamps from the chips given off by the milling cutters the latter are separated from the former by a casing attached to or formed in part by the frame and provided with an opening 80 for the passage of the clamp frame 63, and in said opening is arranged a self closing door 81 which yields to the advance of said frame and permits the passing to and fro of the clamps.

Suitably supported upon the frame to the left of the clamp frame 63 is a removable supply galley 90 the open end whereof abuts against a block 91 and registers with an opening 92 therein through which the matrices pass, the end of the column being arrested by a wall 93, forming one side of a transverse channel 94 terminating at one side of the opening through which the clamp frame reciprocates. A follower 95, traveling on a guide and connected to a weight 96 through cord 97, the latter passing around properly disposed pulleys, serves to advance the column of matrices as the front member in channel 94 is removed.

The receiving galley is suitably supported on the right of frame 63 with its open end in register with a gate or passage 98 containing retaining springs 99 and opening into a transverse channel or way 100 terminating at one end in the opening or passage for the clamp frame 63 and provided with a spring retaining pawl 101.

The floors of channels 94, 100, are on different levels separated the distance between the two sets of jaws of the translating devices so that when frame 63 is shifted to position the jaws in the space between proximate ends of said channels, the upper jaws will register with channel 100 and the lower with channel 94 as indicated in Fig. 34, in which position lever 79 registers with the actuating rod 74 of the lower clamp as in Fig. 22, and operating thereon opens the clamps for the admission of a matrix. The

matrix transferring devices include the two pushers 102 and 103 whereof the first operates to simultaneously transfer a matrix from the end of the supply column to the lower and opened clamp of the translating device and to discharge the finished matrix from the upper clamp into channel 100 whereas the second pusher (103) operates to transfer the matrix thus delivered to the receiving galley.

Pusher 102, Fig. 39, is carried by a slide 104 reciprocating in ways on the frame and is formed or provided with two engaging faces the lower (105) riding in channel 94 and the upper (106) at the end of a reduced extension adapted to pass between the jaws of the upper clamp and advance the matrix into channel 100, beyond retaining pawl 101. Pusher 103, Fig. 40, is carried by a slide 106^x supported to reciprocate transversely of slide 104 in guides on the frame and operates across the rear end of channel 100 in line with the entrance to the receiving galley. Opposite the shorter lower section of pusher 102 is an abutment 107 serving to engage the position of the matrix when introduced into the lower clamp.

With the exception of the means for rotating the milling cutters hereinbefore described, the several mechanisms receive their motions from a single cam shaft 108, coupled with pulley 14 through gears 108^x, shaft 109, and worm gearing 110, Figs. 1, 2 and 4, as follows: The milling cutter carriage 6 is connected by link 111 with a lever 112, the latter bearing a roller engaging grooved cam 113 (Figs. 3 and 48); the actuating rod 24 is advanced to open chuck jaw 19 by the engagement of a lever 114 (Fig. 5) whose lower arm carries a roller in contact with cam 115, Fig. 46; the centering pin spindle actuating lever 37, Fig. 5, is acted upon in a direction to advance said spindle by a spring 117 and in opposition thereto by a cam 118, Fig. 44; the locking bolt 42 and slide 60 of the translating devices are coupled together and connected by a link 119 to a lever 120, the latter moved in one direction by a spring 121, Fig. 5, and in the opposite direction by a cam 122, Fig. 45; rack 62 of the translating devices is oscillated by a link 124 connected to a lever 125 engaged by cam 126, Fig. 47; slide 78 for effecting the vertical movements of clamp frame 63 of the translating devices is connected by link 127 to lever 128 the latter controlled by cam 129, Fig. 43; carriage 65 of the translating devices is coupled with a cam 130, Fig. 41, through a lever 131, opposed springs 132 on link 133, rack 134, segment 135, shaft 136, segment 137 and rack 138, the latter on said carriage; lever 79 for opening the clamps of the translating devices is coupled with cam 139, Fig. 41, through a shoe 140, Figs. 19, 20 and 21, riding on rod 141, carried by piv-

oted frame 142, the latter connected by link 143 with lever 144, engaging cam 139, Fig. 41; pusher 102 receives motion from cam 146, Fig. 42, through lever 147, the latter en- 5 gaging a block 148 free to slide on a rod 149 attached to slide 104, said rod provided with limiting shoulders and a spring 150 through which the advance of the pusher is effected; and pusher 103 derives its movement from 10 cam 115 through lever 114, springs 151, rod 152 and bell crank lever 153, Fig. 2.

Summary of operations: Assuming the milling cutters to be operating upon a matrix in the positioning and holding devices 15 and that the translating devices have been retracted to bring the upper and lower clamps in register with channels 100 and 94, respectively, lever 79 is actuated to open the lower clamp and pusher 102 is advanced to 20 thrust a matrix from channel 94 into the lower clamp and to discharge the finished matrix from the upper clamp into channel 100 followed by a return of lever 79 to close the lower clamp and of pusher 102 to clear 25 the upper clamp. While this is taking place, carriage 6 is first drawn down as indicated in Fig. 28, causing cutter 3 to traverse across the matrix and form a groove 1 in one side thereof, after which slide 6 is again elevated 30 until cutter 3 is above the matrix, whereupon centering spindle 30 is slightly withdrawn, yoke 60 is lowered to withdraw locking bolt 42 and engage pawl 44, and pinion 43 is moved to give chuck carrying sleeve 16 35 a quarter turn. Yoke 60 is next elevated to withdraw pawl 44 and engage bolt 42, and pinion 43 returns, and, in the meantime, carriage 6 is elevated to cause cutter 4 to pass the matrix as shown in Fig. 29. Carriage 6 40 returning to its intermediate position, the devices operate as before to give sleeve 16 a one quarter turn, whereupon carriage 6 is again drawn down to cause cutter 3 to traverse the matrix, Fig. 30, and upon the re- 45 turn of the carriage to intermediate position sleeve 16 is again turned one quarter around followed by the elevation of carriage 6 to cause cutter 4 to form its second cut and the last of the four performed. 50 Carriage 6 having resumed its intermediate position carriage 65 of the translating devices is advanced and slide 78 lowered until the upper clamp is brought opposite and be- 55 tween the chuck and centering spindle. Dur- 60 ing the forward and downward motion of the clamps the actuating rod 74 of the upper clamp is brought into register with lever 79 and the latter is actuated to open said clamp so that its jaws will clear the finished matrix held in the chuck. Lever 65 114 is now actuated to open the chuck and advance block 27, at the same time the centering spindle 30 is retracted, the finished matrix being thus deposited in the upper clamp, Fig. 26, and confined therein by the

closing of the movable jaw. Frame 63 is next elevated to bring the lower clamp containing the ungrooved matrix between the chuck and centering spindle, Fig. 27, whereupon the centering spindle is advanced 70 thereby pressing the matrix endwise into the jaws of the chuck until arrested by block 27, when the chuck is closed, the centering spindle pressed home, lever 79 operated to open the lower clamp, and the translating 75 devices are withdrawn to initial position. Concurrently with the opening of the chuck for the discharge of the finished matrix pusher 103 is actuated to remove the matrix previously deposited in channel 100 into the 80 receiving galley.

Having thus described my invention, what I claim as new, and desire to secure by Letters Patent of the United States, is:—

1. In a machine such as specified, the combination of the following elements, to-wit: a plurality of rotary cutters mounted upon a carriage; a rotatable blank holder; means for reciprocating said carriage to present the cutters successively to the blank; and 90 means for effecting a partial rotation of the holder in the interval between successive applications of the cutters. 85

2. In a machine such as specified, the combination of the following elements, to-wit: 95 a reciprocating carriage provided with a plurality of rotating cutters disposed in sequence in the line of movement of said carriage; a rotatable blank holder located to one side of the path of said cutters intermediate opposite extremes of their reciprocating movements; means for reciprocating said carriage in alternately opposite directions relative to the position occupied by the blank holder, to bring the cutters alternately into engagement with a blank confined in the holder; and means for giving the blank holder a partial rotation in the intervals between successive engagement of the cutters with the blank. 100 110

3. In an automatic milling machine, the combination of the following elements, to-wit: a plurality of dissimilar milling cutters mounted upon a carriage and arranged in sequence in the direction of movement of 115 said carriage; a rotatable blank holder located intermediate the cutters and provided with actuating devices for effecting successive partial rotations of said holder and for locking the latter in the interval between 120 said rotative movements; and actuating devices for reciprocating said carriage alternately in opposite directions in the intervals between successive movements of the blank holder about its axis. 125

4. In an automatic milling machine, the combination of the following elements, to-wit: a carriage carrying two milling cutters disposed in sequence in the direction of motion of said carriage; means for re- 130

- ciprocating said slide; a blank holder located to one side of the path traversed by the cutters and intermediate the opposite extremes of said path so that said cutters 5 will be caused to act successively upon a blank in said holder, and means for effecting successive partial rotation of the holder about its axis in the intervals between the successive engagements of alternate cutters 10 with the blank.
5. In an automatic milling machine, the combination of the following elements, to-wit: a plurality of milling cutters supported to reciprocate in unison; a rotatable blank 15 holder located to one side of the path traversed by said cutters and intermediate the opposite extremes of said path; and a centering device for the blank opposite and in axial alinement with said holder.
- 20 6. In an automatic milling machine, the combination of the following elements, to-wit: a rotatable blank holder provided with intermitting actuating and locking means; a plurality of milling cutters supported to 25 reciprocate in unison transverse to the axis of the blank holder and to one side thereof; and actuating devices coupled with said blank holder actuating and locking means and the support for the cutters, the same 30 operating to reciprocate the cutters alternately in opposite directions relative to the blank holder to cause alternate cutters to pass said holders, and to effect a partial rotation of the blank holder in the interval between successive passes of the cutters.
- 35 7. In an automatic milling machine provided with a plurality of rotating cutters supported to reciprocate in unison and in combination therewith, matrix positioning 40 and supporting devices located in proximity to the path traversed by said cutters including the following elements, to-wit: a rotatable spindle provided with a chuck adapted to grasp one end of the matrix, and an opposed centering spindle adapted to enter a cavity in the opposite end of the matrix.
- 45 8. In an automatic milling machine provided with a plurality of rotary cutters supported to reciprocate in unison and arranged in sequence in the direction of said movement and in combination therewith, means for positioning and supporting a blank or matrix and presenting successive sides thereof in the path traversed by alternate cutters, the same including the following elements, to-wit: a rotatable spindle provided with intermittent actuating devices for effecting progressive rotary movements, locking means, and a chuck equipped with 50 positioning or gaging jaws, said spindle being disposed at an angle to the path traversed by the cutters with its chuck to one side of and intermediate the opposite extremes of said path; a centering spindle on 55 the opposite side of the path traversed by the cutters and in axial alinement with the chuck; and actuating devices coupled with the cutter support and said intermittent actuating devices for reciprocating the cutters alternately in opposite directions relative to the chuck and in the intervals turning the chuck to present different sections or faces of the block in the path of the cutters. 70
9. In an automatic milling machine for matrices and the like, the combination of the following elements, to-wit: a milling mechanism including two rotary cutters supported to reciprocate in unison and disposed in sequence in the direction of their motion of translation; matrix positioning and holding devices located in proximity to the path traversed by said cutters and comprising a rotatable chuck and opposed centering spindle; and translating devices receiving completed matrices from and delivering blank 80 matrices to the chuck.
- 85 10. In an automatic milling machine, for matrices, the combination of the following elements, to-wit: milling devices including a plurality of reciprocatory cutters arranged in tandem in the direction of their motion of translation, to bring the cutters successively into action upon a blank presented at a point intermediate the opposite extremes of said motion, matrix positioning and holding devices to hold said matrix at said point, including a rotatable chuck provided with means for opening and closing the same and a centering spindle in axial alinement with said chuck and provided with means for reciprocating said spindle; and translating devices provided with a plurality of clamping jaws movable between the chuck and centering spindle. 90
- 95 11. In an automatic milling machine for matrices and the like, the combination of the following elements, to-wit: two milling cutters supported to alternately reciprocate in the same path from opposite ends thereof; and blank positioning and holding devices located adjacent the path traversed by said cutters and including a rotatable chuck and opposed centering spindle in axial alinement, and means for transmitting intermittent rotary motion to said chuck, for opening and closing the latter, and for reciprocating the centering spindle. 105
- 110 12. In an automatic milling machine for matrices and the like, the combination of the following elements, to wit; two milling cutters supported to alternately traverse the same path; and a blank positioning and holding device located adjacent said path and extending transversely thereof, the same including a rotatable chuck and a centering 115 spindle in axial alinement with the chuck. 120
13. In milling machines for matrices and the like, the combination of the following elements, to-wit; two rotary cutters supported to alternately traverse the same path and 130

to approach the latter from opposite directions; a blank positioning and holding device located adjacent said path and including a rotatable chuck with its axis disposed 5 in a line transverse to the direction of motion of the cutters; and means for effecting a partial rotation of the chuck in the interval between the traverse of successive cutters.

14. In a milling machine for matrices and 10 the like, the combination of the following elements, to wit; a milling mechanism provided with two cutters and means for reciprocating the latter alternately in opposite directions with relation to an intermediate 15 point or station; a rotatable blank holding chuck located in proximity to said intermediate point or station and to one side of the path traversed by said cutters; and automatic means for effecting a partial rotation 20 of the chuck and automatic means for opening the chuck after a predetermined number of said rotary movements.

15. In a milling machine for matrices and the like, provided with two rotary cutters 25 and means for reciprocating the latter alternately in opposite directions with relation to an intermediate point or station, and in combination therewith, a matrix positioning and holding device located adjacent said 30 intermediate point or station and including a rotatable chuck provided with clamping jaws having angular seating or gripping faces; a centering spindle in axial alinement with said chuck, means for gaging the 35 position of the blank or matrix within the chuck; means for intermittently rotating the chuck; means for opening and closing the clamping jaws; and means for reciprocating the centering spindle longitudinally, to permit the withdrawal of a blank from the 40 chuck and to thrust an interposed blank between the clamping jaws.

16. In a matrix positioning and holding device for automatic milling machines, the 45 combination of the following elements, to-wit: a revoluble hollow sleeve or spindle; a chuck mounted upon said spindle and provided with radial clamping jaws and an axial guide; a gage block movable in said 50 guide; actuating devices for the chuck jaws carried by said spindle; and a slide coupled with the gage block and carried by the spindle in position to be engaged by the chuck jaw actuating devices when the latter are 55 advanced to open the chuck.

17. In a milling machine such as described, the combination with a reciprocatory cutter, of a blank positioning and holding mechanism including the following elements, to wit; a revoluble chuck provided 60 with angular clamping jaws, a movable gage and means for intermittently rotating said chuck, reciprocating the gage, and opening and closing the clamping jaws; a reciprocatory centering spindle in axial alinement

with the chuck; and a pusher carried by said centering spindle and coupled therewith through a yielding connection.

18. In a milling machine such as described, provided with a reciprocatory cutter and an intermittently revolving chuck, and in combination therewith, a blank centering and seating mechanism including the following elements, to-wit: a longitudinally movable centering spindle in axial alinement with the chuck; a pusher surrounding the centering spindle; actuating devices coupled with the centering spindle; and a spring interposed between said actuating devices and pusher.

19. The combination with the intermittently revolving blank positioning and holding chuck provided with an axially movable gage, of an opposed longitudinally movable centering spindle, a pusher surrounding said spindle and carried upon rods lying in longitudinal grooves therein, a spring interposed between said spindle and a collar attached to said rods, and means for reciprocating the spindle.

20. In a machine such as specified, the combination of the following elements, to-wit: a reciprocatory milling mechanism; a blank positioning and holding mechanism including a revoluble chuck provided with actuating devices for automatically opening and closing its clamping jaws and for intermittently revolving said chuck; and a blank centering and seating mechanism including a longitudinally movable centering spindle in axial alinement with the chuck and a pusher surrounding said spindle.

21. In a machine such as specified, the combination of the following elements, to-wit: reciprocatory milling devices; blank positioning and holding devices, including an intermittently revoluble chuck; blank centering and seating devices including a centering spindle in axial alinement with said chuck; and translating devices provided with two clamps, means for opening and closing said clamps, and means for successively presenting alternate clamps opposite the chuck and subsequently withdrawing both clamps.

22. In an automatic milling machine, such as described, the combination of the following elements, to-wit: a reciprocatory milling mechanism; blank positioning and holding devices, including an intermittently revolving chuck and means for opening and closing the jaws thereof; blank centering and seating devices, including a longitudinally movable centering spindle; and translating devices including a reciprocatory frame provided with a plurality of clamps, and actuating devices for presenting the clamps alternately to the chuck and for opening and closing the clamp so presented, the one to receive the finished article from

and the other to present a blank to the chuck.

23. In an automatic milling machine, such as described, the combination of the following elements, to-wit: reciprocatory milling devices, including a plurality of cutters arranged in sequence in the direction of travel; blank positioning and holding devices including an intermittently revolving chuck and actuating devices therefor; blank centering and positioning devices including a longitudinally movable centering spindle in axial alinement with the chuck and actuating devices for said spindle; and blank translating devices including two sets of clamps connected to move in unison and actuating devices for presenting alternate clamps to the chuck and for opening and closing said clamps.
24. In a blank translating or feeding mechanism for automatic milling machines, such as described, the combination of the following elements, to-wit: a two-way movable frame provided with two sets of clamping jaws; and actuating devices for shifting said frame to present alternate sets of clamping jaws at a predetermined point or station, and for opening and closing the jaws.
25. In a blank translating or feeding mechanism for milling machines, such as described, the combination of the following elements, to-wit: a reciprocatory carriage; a frame pivotally supported upon said carriage and provided with two sets of clamps each equipped with a movable jaw; and an actuating device mounted upon said carriage in position to control the movable jaw of either clamp.
26. In a blank translating or feeding mechanism for milling machines, such as described, the combination of the following elements, to-wit: a reciprocatory carriage; a frame pivoted upon said carriage and provided with two sets of clamping jaws whereof one jaw of each set is movable and provided with an actuating rod; and an actuating lever mounted upon the carriage in position to engage either of said jaw-actuating rods according to the angular position of said frame.

27. In a milling machine provided with reciprocatory cutters and an intermittently revolving blank holding chuck, and in combination therewith, translating devices for the blanks including a reciprocatory carriage, a frame pivotally supported thereon and provided with a plurality of clamps the movable jaws whereof are each coupled with an actuating rod, means for reciprocating the carriage and vibrating the clamp frame to present alternate clamps to the chuck; and an actuating member mounted upon the carriage in position to engage the jaw actuating rod of either clamp.

28. In a milling machine, the combination of the following elements, to-wit: a reciprocatory milling cutter; a blank positioning and holding mechanism including an intermittently revolving chuck; blank seating and centering mechanism; a translating device including a two-way movable frame provided with a plurality of clamps, means for opening and closing said clamps separately and means for reciprocating the frame to present alternate clamps to the chuck, the one to receive a blank from and the other to present a blank to the chuck; supplying and receiving galleries; and means for transferring blanks from the supplying gallery to one set of said clamps and from the other set of clamps to the receiving gallery.

29. The combination with a two-way movable frame equipped with a plurality of clamps, a supplying gallery provided with a discharge passage on a level with one of said clamps, a receiving gallery provided with an entrance gate on a level with the other clamp, and a transferrer provided with engaging members of different extent or projection, the shorter working in the discharge passage of the supplying gallery and the longer through the other clamp into the entrance gate of the receiving gallery, to simultaneously charge one clamp and discharge the other clamp.

30. In an automatic milling machine, such as described, provided with translating devices equipped with a plurality of clamps, and in combination therewith, a supply gallery in open communication with a transverse channel terminating at one side of the path traversed by the translating devices; a receiving gallery in open communication with a transverse channel terminating at the opposite side of the path of the translating device and displaced laterally of the first named channel an amount corresponding with the relative positions of the clamps, a pusher working in the first named channel and provided with a projection in the plane of the second channel; and a pusher working through the second channel in line with the receiving gallery.

31. In an automatic milling machine, the combination of the following elements, to-wit: a reciprocatory milling mechanism including two cutter bearing shafts in parallel relation in the plane of their motion of translation; a rotatable chuck with its axis in parallel with the cutter shafts and to one side of their plane of movement; a blank translating device provided with a plurality of clamping jaws movable transversely of the axis of the chuck; and means for transferring a blank from the chuck to one set of clamping jaws and from the other set of clamping jaws to the chuck.

32. In an automatic milling machine, the

combination with cutting and work positioning and holding devices separated by a partition, of translating devices for the blanks movable toward and from the work positioning and holding devices, and a self-closing door interposed in the path of said translating devices between the latter and the cutting devices.

33. A blank translating mechanism for 10 automatic milling machines such as described, including in combination, the following elements, to-wit: a reciprocatory carriage; a frame pivotally mounted upon said carriage and provided with two sets of 15 clamping jaws disposed in sequence in the plane of vibration; and means for guiding and vibrating said frame, including a slide movable transversely of the line of motion of the carriage and engaging said frame at a 20 point remote from its pivot.

34. A blank translating mechanism for 25 automatic milling machines, such as described, including, in combination, the following elements, to-wit: a reciprocatory carriage; a frame pivotally mounted upon said carriage; a slide movable transversely of the line of motion of the carriage and engaging said frame to guide and oscillate the latter;

two clamps mounted upon said frame and each provided with a movable jaw and actuating member, the latter disposed in sequence in the plane of vibration of said frame; and an actuating member mounted upon the carriage in position to register with alternate clamp actuating members.

35

35. In a blank positioning and holding mechanism for automatic milling machines such as described, provided with a chuck and intermittent rotating devices therefor and in combination therewith a locking and gaging 40 or final positioning means for said chuck the same including a notched disk and a sectional locking bolt movable longitudinally between fixed guides, the rear or actuating section of said bolt over-lapping the front or 45 engaging section and provided with an inclined engaging face operating, when the bolt is advanced into engagement with the notched disk, to force the front section laterally into contact with one of its fixed guides. 50
